Inventor:
Arthur W. Buck,
By Hugh K. Wagner,
Atty.

UNITED STATES PATENT OFFICE.

ARTHUR W. BUCK, OF ST. LOUIS, MISSOURI.

MEANS FOR CAUSING REGISTRATION OF RÖNTGENOGRAPHS.

Application filed January 14, 1921. Serial No. 437,346.

To all whom it may concern:

Be it known that I, ARTHUR W. BUCK, a citizen of the United States, residing at the city of St. Louis, in the State of Missouri, have invented certain new and useful Improvements in Means for Causing Registration of Röntgenographs, of which the following is a specification.

This invention consists of a method of 10 doubling or multiplying the intensity or density of the lines and other parts of an X-ray photograph or röntgenograph and an instrument for practicing that process. It may be used in connection with dental 15 X-ray films or any others.

As now constructed, the best dental-film packets contain two pieces of film material. This is now only for the purpose that one photograph may be given to the patient and 20 the other retained by the dentist. Such packets can be made and used with three or more films therein, if desired, and for the practice of the method herein described and for the purpose herein mentioned such pluralization will be desirable in some instances, as, for instance, for cases where it is 25 found particularly difficult to obtain a clear picture.

In the accompanying drawings forming 30 part of this specification, in which like numbers of reference denote like parts wherever they occur,

Figure 1 is a front elevation;

Figure 2 is a side elevation of an instrument 35 for practicing this method.

In the present construction of dental X-ray film packets, the plurality of pieces of film therein are in registration with each other. Therefore, when a photograph is 40 made, it is not only the same on each film, and not only are the same in registration with each other, but they are capable of being realigned, so as to register with each other again.

When two or more underexposed or underdeveloped films, which would ordinarily possess little, if any value, are thus returned to exact registration together, the intensity or density and, therefore, the visibility of 45 the detail and contrast of the röntgenograph is multiplied when held between the eye and the light for examination.

The underexposed or underdeveloped röntgenographs are given a utility and value 50 that they would not otherwise possess, obviating at least the time, delay, trouble, and

expense of retaking and, in many cases, relieving from the necessity of summoning the patient for another engagement.

The use of this process and instrument is 60 useful even in the case of röntgenographs of good quality, as thereby even their showing is improved and greater clearness is obtained with respect to the details of the structure of specially delicate tissues. 65

This method or process consists in the reregistration of films for the purpose above described, which reregistration must necessarily be exact, and viewing the same by transmitted light. 70

The instrument illustrated in the drawings combines the functions of enabling the said necessary accurate reregistration of the röntgenographs; their efficient holding in such alinement; their protection from outside reflection or the like; and their convenient handling while being viewed. 75

This device consists of a handle 1, a frame 2, having the cross-member 3, which underlies and supports the films 4 and causes their lower edges to aline with each other, thereby producing registration of the pictures that they bear. The side members of this frame 2 force vertical alinement of the said 80 films and pictures just like the cross-member 3 produces horizontal alinement thereof. 85

The films 4 are placed between a pair of pieces 5 and 6 of optically perfect glass, commonly known as optical flats, the same being vertically (as shown in the drawings) 90 slightly smaller than the films 4. This enables pressure with a finger upon the upper edges of the films 4 when located between the glasses 5 and 6; thereby forcing the same to rest fully on their bottom edges on cross-piece 3, being guided and held in such movement by the side members of frame 2. The upper edges of the films 4 project slightly above the top edges of the glasses 5 and 6. 95

Around the outside edge of the glasses 5 and 6 extends an opaque strip or band 7, either enameled thereon or otherwise applied thereto, its object being to exclude outside reflection and the like. 100

A spring or a plurality of springs 8 hold 105 the glasses 5 and 6 and the films 4 in place and press the same toward a holding member or frame 9, which is attached by screws 10 to frame 2. Screws 11 fasten springs 8 to frame 2. An opening 12 through frame 110 9 permits viewing the röntgenographs therethrough.

The inner side of cross-member 3 and of the side members of frame 2 are preferably grooveless, as thereby perfect registration is more easily secured.

5. If desired, a permanent stand or the like may be substituted for the handle 1.

Having thus described this invention, I hereby reserve the benefit of all changes in form, arrangement, order, or use of parts, 10 as it is evident that many minor changes may be made therein without departing from the spirit of this invention or the scope of the following claims.

I claim:

15. 1. An instrument of the character described, consisting of a frame and a pair of glasses, a film positioned between said glasses and another frame adapted to hold the said glasses from one side and a spring on the 20 other.
2. An instrument of the character described, consisting of a frame and a pair of glasses, a film positioned between said

glasses and another frame adapted to hold the said glasses from one side and a spring 25 on the other, the said spring and the said last-mentioned frame being attached to the said first-mentioned frame.

3. An instrument of the character described comprising a frame, a holding member borne thereby and provided with an opening, optical flats held in the frame by the holding member on one side and arranged in front of said opening, a film between the flats, and a spring to hold said flats on the 35 other side.

4. Means for causing registration of röntgenographs including a frame equipped with optical flats, said frame being open on one side for insertion of a sensitized body 40 between the flats, and means to hold the flats in engagement with said body.

In testimony whereof I hereunto affix my signature.

ARTHUR W. BUCK.
